UNITED STATES PATENT OFFICE

GEORGE W. LANE, OF PROVIDENCE, RHODE ISLAND, ASSIGNOR TO RAU FASTENER COMPANY, OF PROVIDENCE, RHODE ISLAND, A CORPORATION OF RHODE ISLAND

SNAP FASTENER

Application filed June 27, 1928. Serial No. 288,633.

This invention relates to an improved construction of snap fastener; and has for its object to provide a socket-engaging stud member and a stud-receiving socket member, the 5 fastener portions of both of said members having a continuous or unbroken surface, the engaging surface of one of said members being of a shape in cross section different from that of the other of said members.

10 A further object of the invention is the provision of a socket member for a snap fastener having a stud-receiving opening with an inwardly-turned edge wall portion, said wall portion having a continuous or un- 15 broken stud-engaging surface and provided with spaced stud-engaging members or wall portions extending inwardly or being of less distance from the center of the opening than the other wall portions of the opening.

20 With these and other objects in view, the invention consists of certain novel features of construction, as will be more fully described, and particularly pointed out in the appended claims.

25 In the accompanying drawings:

Fig. 1 shows a blank as cut from sheet stock from which the socket member is formed.

30 Fig. 2 shows the blank as drawn up into cup shape, with an opening thru its top plate.

Fig. 3 is a top view showing an opening thru the top plate.

35 Fig. 4 is a top view showing the opening thru the top plate as formed generally circular in contour, the circle having flattened portions or chords providing inwardly-extending stud-engaging portions.

40 Fig. 5 is a perspective view showing the plunger or punch with generally circular contour and having flattened sides for forming a similarly shaped and stud-receiving opening in the socket member.

Fig. 6 is a section on line 6—6 of Fig. 5.

45 Fig. 7 is a sectional elevation showing the margin of the opening of the socket as turned inwardly with flattened surfaces produced by action of the plunger.

50 Fig. 8 is an elevation showing one form of stud member of the fastener with a circular engaging surface.

Fig. 9 is a section on line 9—9 of Fig. 7 and showing the circular stud in engagement with the socket member.

Fig. 10 shows the socket member with a 55 circular opening.

Fig. 11 shows a stud member with an engaging surface having spaced flattened portions.

Fig. 12 is a top view showing the stud having its engaging surface flattened at spaced 60 points around its periphery.

It is found in the practical construction and operation of snap fasteners particularly fasteners of the heavier type such for instance as those used on curtains, carpets and other 65 heavy materials, of advantage to form the fastener with a very strong grip; also to provide a fastener in which the socket member is formed of one piece to reduce the cost of

construction and at the same time provide 70 a fastener which is strong and durable; and to accomplish this in a simple and effective way, I have formed a socket member plate with a stud-receiving opening, the edge of the

opening being turned inwardly and the engaging portion providing a continuous or unbroken surface, that is this engaging surface is not split to form spring fingers as is usual in the formation of such sockets and during the turning in of this edge portion I 75

flatten the stock. The turning in of this edge portion may be accomplished by the use of a punch or plunger having flattened sides thereby forming spaced flattened surfaces in the walls of the socket which form inward-

80 extending stud-engaging portions and in some other cases instead of forming flattened sides in the socket opening I may form the

85 socket member with a circular opening and form the flattened sides on the stud member, as illustrated in Figs. 11 and 12, in both

80 of which cases the stud member or the socket member is formed with a continuous or un-

90 broken surface and is not split to form spring-engaging fingers; and the following is a de-

95 tailed description of the present embodiment of my invention and showing the preferred means by which these advantageous results may be accomplished.

With reference to the drawings, 10 desig-

nates the blank of the socket member which may be formed of sheet material and with peripheral fastening prongs 11. This blank is then drawn up into thimble or socket shape, as illustrated in Fig. 2, and the center portion of the top plate is punched out leaving a hole 12, the prongs being turned inwardly to pierce the fabric to which the socket is to be fastened.

10 In order to form this stud-receiving hole with the required flattened sides 13, I employ a punch and die, the punch being formed as best illustrated in Fig. 5, having a generally circular shank 14 with flattened sides 15 arranged in spaced relation about its surface. This punch is then forced thru the opening 12 which serves to turn inwardly the edge 16 of this opening into the shape best illustrated in Fig. 7 and at the same time the 15 flattened portions 15 of the punch form correspondingly flattened portions or chords 17 engages these flattened chords in the socket member and when a circular stud 18 is caused to be forced into the socket member the stud 20 engages these flattened chords in the socket and has a tendency to force these chords outwardly into circular form while snapping past the same, whereby these chords will engage the undercut neck portion 19 of the stud 25 under the head, as best illustrated in Fig. 9 to releasably retain the stud in its socket.

In other instances, instead of forming the flattened spaced portions on the walls of the socket opening, I may form a socket member 30 with a circular stud-receiving opening 21, as best illustrated in Fig. 10, and in this case I form a stud member 22 with spaced flattened portions 23 formed about its engaging surface, whereby the extending arcuate 35 portions 24 being of a diameter slightly greater than the circular opening 21 in the cooperating socket opening, these arcuate portions upon being forced into the socket have a tendency to either flatten and so snap 40 into the socket or the walls of the opening in the socket may be distorted to permit the entrance of the stock to detachably secure the two members together.

I have herein shown and described the stud 45 and the socket or either one of them as having a generally circular engaging surface with flattened portions, but one of these engaging members may be formed of any shape other than circular, in a horizontal section if desired, such for instance as oblong or square, or other shape so that but a portion of the whole surface of the socket opening may be engaged.

50 My improved snap fastener is very simple and practical in construction and the socket in this case is formed of one piece of metal and therefore, may be constructed with the minimum cost of manufacture.

The foregoing description is directed solely 55 towards the construction illustrated, but

I desire it to be understood that I reserve the privilege of resorting to all the mechanical changes to which the device is susceptible, the invention being defined and limited only by the terms of the appended claims.

70

I claim:

1. A snap fastener comprising a socket engaging stud member and a stud receiving socket member, the fastening portion of one of said members being circular in outline, and the cooperating fastening portion of the other of said members being substantially circular in outline with spaced recesses, the fastening portions of both members having a continuous, unbroken surface, the members engaging and disengaging each other by direct snapping action upon direct axial movement with respect to each other.

75

2. A snap fastener comprising a socket engaging stud member and a stud receiving socket member, the fastening portion of the stud member being circular in outline, and the cooperating fastening portion of the socket member being substantially circular in outline with spaced recesses, the fastening portions of both members having a continuous, unbroken surface, the members engaging and disengaging each other by direct snapping action upon direct axial movement with respect to each other.
